UNITED STATES PATENT OFFICE.

ALONZO HITCHCOCK, OF NEW YORK, N. Y.

DRAFTSMAN'S T-SQUARE.

SPECIFICATION forming part of Letters Patent No. 274,194, dated March 20, 1883.

Application filed May 6, 1882. (No model.)

To all whom it may concern:

Be it known that I, ALONZO HITCHCOCK, of the city, county, and State of New York, have invented certain new and useful Improvements 5 in Draftsmen's T-Squares; and I do hereby declare that the following is a full, clear, and exact description thereof, reference being had to the accompanying drawings, and to the letters of reference marked thereon, making a part of 10 this specification.

My invention relates to improvements in the construction of draftsmen's T-squares.

The object of my invention is to furnish a suitable head for a T-square which shall be 15 independent of the blade, and to which any one of a set of separate blades may be readily attached and be adjusted to any angle.

It consists of a straight-edged metallic plate, adapted either to constitute in itself a head for 20 a T-square or to be secured to an ordinary wooden T-head, and which is formed with an offset or lip projecting from and beyond its straight edge, midway of its length, to rest upon the face of the drawing-board as a support for the head, the width of said offset or 25 lip being equal to or less than that of the blade of the square, so as to permit the head to be tipped in either direction when required, and which is likewise provided with a flange or shoulder along the under side of its straight 30 edge, to serve as a guide for the head against the edge of the drawing-board, said flange being formed continuously in one piece with the head along its entire length, or at intervals 35 in the form of lugs, or otherwise secured by the attachment of the metallic head to a wooden head whose inner straight edge, coinciding with that of the metallic head, shall constitute its guiding-flange. This part of my 40 invention enables me to furnish at a low cost a correct and exact T-head, adapted for use in and of itself as an independent head, or which may be combined with a simple straight wooden head to produce cheaply a long head for the square, where such is preferred.

It consists, secondly, in uniting the blade of 45 the square to the separate metallic head-plate by means of an interposed separate metallic connecting-plate adapted to be pivoted to the metallic head and rigidly secured to the blade,

and which finds support upon the central lip projecting from the straight edge of the head. This part of my invention supplies, in connection with the independent metallic T-head, a ready and inexpensive method of uniting thereto any suitable blade, and permits of an interchange of blades of different lengths with the same head, and of its adjustment to any required angle, as may be desired. 55

In the accompanying drawings, Figure 1 is 60 a plan view of my improved independent head constructed to form in itself a complete head for the T-square, and Fig. 2 a central transverse section thereof in line *xx* of Fig. 1. Fig. 3 is a plan view of the under side of the connecting-plate when attached to the blade of the square, and Fig. 4 a transverse section thereof in line *yy* of Fig. 3. Fig. 5 is a plan view of my improved head when constructed in simplest cheapest form for attachment to a 65 wooden T-head, showing it so attached, Figs. 6 and 7 being similar views of modifications thereof, (the latter being drawn upon a reduced scale to embrace the whole length of the T-head;) and Fig. 8, a section in line *zz* of Fig. 5, illustrating a special form of socket for the end of the clamping-screw. Fig. 9 is a plan view of the under side of the connecting-plate, adapted for use with the head shown in Fig. 5, and its modifications. Fig. 10 is a plan 70 view of a metallic T-head, with the connecting-plate carrying the blade secured in place thereon to constitute a complete T-square, Fig. 11 being a central section thereof in line *ww* of Fig. 10, showing its application to a 75 drawing-board. Fig. 12 is a sectional view of the independent head, Fig. 5, when secured upon a wooden T-head, with the connecting-plate carrying the blade secured in place thereon, making a complete T-square. Fig. 13 80 illustrates an independent T-head when constructed in extended form for large work. Fig. 14 is a section in line *tt* of Fig. 13, illustrating the application of that form of head to a drawing-board, the blade-plate being omitted. Fig. 15 is a plan view of a detachable metallic head for a wooden T-head constructed 85 without a projecting flange. 90

A is a metallic head-plate for a T-square, which may be cast in light ornamental form, 95

with the necessary straight edge *a*. From the center of this straight edge *a* an offset or lip, *B*, of a width not exceeding that of the blade of the T-square, is formed to extend at a right angle 5 with said edge in a plane parallel to that of the plate, so that it may afford a bearing for the head upon the face of the drawing-board when the straight edge *a* is brought in line with the edge of the board. When the head- 10 plate is designed to serve in itself as the head of the T-square, a flange or shoulder, *C*, (see Fig. 14,) is formed to project along the under side of its straight edge *a*, for the purpose of bearing against the edge of the drawing-board, 15 over and upon which the lip *B* projects and rests. Instead of making said flange continuous along the entire length of the edge *a*, Fig. 14, two or more lugs may be substituted there- 20 for to perform the same function. When the head-plate is designed for use in combination with a wooden T-head (see Figs. 5, 6, and 7) the flange *C* may be omitted, the edge of the wooden head furnishing in such case the required bearing against the drawing-board. 25

The connection of the blade *P* with the head *A* of the T-square is effected by means of a metallic connecting-plate, *D*, adapted to be secured at one end to the blade, so as to form, in effect, an extension thereof, and to rest and 30 rotate at the other upon the face of the head-plate, to which it is pivoted. The pivotal connection is formed by means of a pivot-pin projecting from the one to pass through a pivot-hole in the other, (in which case a nut is let 35 onto the end of the pivot-pin to clamp the two together when properly adjusted,) or, as illustrated in the drawings, by means of an annular groove, *m*, formed in the face (or in an offset from the face) of the plate *D*, to receive a 40 counterpart annular projection, *n*, upon the face of the head *A*, the projection *n* and groove *m* being made to fit and interlock with great accuracy and to move upon each other with ease, so as to form a perfect annular pivotal 45 joint, having such an extended bearing as shall insure exactness and precision of adjustment and movement. The two plates *A* *D*, when thus pivoted or hinged together, are secured and at pleasure locked by means of a central 50 clamp-screw, *E*, Figs. 10 and 11, whose head is fitted in a seat countersunk in the under side of the head-plate, and whose shank, extending up through the head-plate at its pivotal center and through a corresponding aperture 55 in the connecting-plate *D*, is fitted upon its outer end with a thumb-nut, *E*. By screwing down this thumb-nut firmly upon the blade-plate the two plates will be bound together, and may thus be locked in any position. 60

The annular joint may be formed upon the projecting lip *B* of the head-plate, as shown in Fig. 1, or upon the body of the head, as shown in Fig. 5. In either case the pivotal center is placed in the middle of the length of the head. 65

The outer free end of the connecting-plate *D* is preferably finished with a point, *k*, to sweep as an index over a scale laid off upon

the arc of a circle described from the center of the annular joint, so that it may serve to indicate the angle at which the connecting-plate and its attached ruling-blade *P* is turned and fixed. In order to more positively lock the blade at a right angle to the straight edge of the head, a set-screw, *F* is fitted in the outer end of the connecting-plate *D*, to pass into a seat provided in the head-plate in position to receive the end of the screw when the blade and head plate are exactly at right angles. By forming additional apertures for the end of the set-screw at different determined points in the head plate, or by passing it through a slot and fitting it with a nut, the same device may be used to lock the blade at any indicated angle. 70

The connection of the detachable head *A* with a wooden T-head, *S*, is simply made by screws *f f*, as shown in Figs. 5 and 6, and the detachable connecting-plate *D* is in like manner readily secured to the blade by the screws *f f*, Figs. 3 and 10. 80

The interlocking grooves *m* and projections *n*, which form the annular joint between the head-plate and detachable blade-plate, are all made to correspond, irrespective of the forms and sizes of said plates, so as to be in all cases 90 interchangeable. By this means a set of blades of different widths or lengths may be used interchangeably with a single head; or the same blade may be fitted to different forms or lengths of heads. 95

Where the head-plate is used in combination with a wooden head, as illustrated in Fig. 8, a metallic seat or socket, *a'*, may be secured in the wooden head to receive and engage the end of a clamp-screw, *G*, Fig. 12, made to screw 105 down into it from the outer side of the blade-plate.

My improved head may be of various forms, as shown in Figs. 1 and 10, 7 and 13, and when designed for use with a wooden T-head may 110 be reduced to very small dimensions, as shown in Figs. 5 and 6, so as to afford simply a seat for the annular joint between it and the blade-plate.

I claim as my invention—

1. The combination, with each other and with the straight inner edge of the head of a T-square constructed independently of its ruling-blade, of a lip, *B*, of substantially the same width as the detached blade, projecting centrally from the straight edge, to provide a support for the head upon the face of the drawing-board, and a flange or shoulder, *C*, projecting along said straight edge at right angles to the lip, to afford a guide for the head 125 against the edge of the board, substantially in the manner and for the purpose herein set forth.

2. The separate blade-connecting plate *D*, in connection with the independent head *A* 130 and a detachable blade, *P*, to connect the blade and head, substantially in the manner and for the purpose herein set forth.

3. The combination of the head *A*, straight

edge a, flange or shoulder C, formed along said straight edge, lip B, projecting centrally from the straight edge at right angles to said flange or shoulder, detachable connecting-plate D, 5 pivoted to the head and resting upon the lip B, and blade P, secured to the plate D, all substantially in the manner and for the purpose herein set forth.

In testimony whereof I have signed my name to this specification in the presence of two sub- 10 scribing witnesses.

ALONZO HITCHCOCK.
